UNITED STATES PATENT OFFICE.

AUGUST HUGO GROSSENBACH, OF WEST HOBOKEN, NEW JERSEY,
ASSIGNOR TO GROSSENBACH & BUTLER, A FIRM, OF NEW YORK, N. Y.

DESIGN FOR BRAID.

SPECIFICATION forming part of Design No. 37,265, dated December 13, 1904.

Application filed November 10, 1904. Serial No. 232,255. Term of patent 3½ years.

To all whom it may concern:

Be it known that I, AUGUST HUGO GROSSENBACH, a citizen of the United States, residing at West Hoboken, in the county of Hudson and State of New Jersey, have invented a new, original, and ornamental Design for Braid, of which the following is a specification, reference being had to the accompanying drawing, forming part thereof.

The figure shows in plan view a braid embodying my design.

I claim as new and desire to secure by Letters Patent—

The ornamental design for braid as shown.
AUGUST HUGO GROSSENBACH.
